(57) **CLAIM**

The ornamental design for a removable drain filter, as shown and described.

DESCRIPTION

FIG. 1 is a front-top perspective view of a removable drain filter showing my new design;

FIG. 2 is a front-bottom perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof;

FIG. 8 is a bottom plan view thereof;

FIG. 9 is a reduced front-top perspective view thereof, wherein the removable drain filter is in an exploded configuration; and,

FIG. 10 is a reduced front-bottom perspective view thereof, wherein the removable drain filter is in the exploded configuration.
